CLAIM

The ornamental design for a combined woodtick and leech remover, as shown and described.

DESCRIPTION

FIG. 1 is a perspective view of a combined woodtick and leach remover, showing my new design;
FIG. 2 is a side elevational thereof, the opposite side being the same except for the switch;
FIG. 3 is a top plan view thereof; and,
FIG. 4 is a bottom view thereof.

FIG. 1.

FIG. 2.

FIG. 4.

FIG. 3.
